UNITED STATES PATENT OFFICE.

GEORGE E. BEHRENS, OF IVORYTON, CONNECTICUT, ASSIGNOR TO JOSEF VEIT, OF NEW YORK, N. Y.

CRUCIBLE-FURNACE.

1,013,472.

Specification of Letters Patent.

Patented Jan. 2, 1912.

Application filed May 11, 1911. Serial No. 626,522.

To all whom it may concern:

Be it known that I, GEORGE E. BEHRENS, a citizen of the United States, residing at Ivoryton, in the county of Middlesex and 5 State of Connecticut, have invented certain new and useful Improvements in Crucible-Furnaces, of which the following is a specification.

This furnace is especially designed for 10 melting metals in a crucible, being constructed to circulate a reducing or non-oxidizing gas over the surface of the metal in the crucible.

The preferred furnace is illustrated in the 15 accompanying drawing, in which the figure is a transverse vertical section, in the plane of the draft-pipe.

The furnace illustrated comprises a cylindrical metal casing 1, the heating chamber 20 of which has a lining 2 of firebrick. A grate 3 serves as a support for the crucible 4 and for the bed of fuel, surrounding the lower part of the crucible. A draft-door 5 opens 25 into the ashpit beneath the grate. The casing 1 is closed at its upper end by a removable top-plate 6. A draft-pipe 7, containing a revoluble damper 8, extends horizontally and then vertically from an opening 9 in 30 the casing 1 above its lining 2. The top 6 has a central opening 10, over which is secured a vertical flue-piece 11, closed at its upper end by a removable cap 12 containing 35 a peep-hole 13. A cross-pipe 14, containing a revoluble damper 15, connects the flue-piece 11 and the draft-pipe 7. A vertical tube 16 extends downward through the opening 10 and into the upper end of the crucible, being removably seated on a shoulder 17 at the lower end of the flue-piece 11. 40 A pipe 18 for supplying hydrogen or other gas opens into the heating chamber. The crucible 4, in large furnaces, may be stationary and provided with an outlet 19 for the molten metal.

45 In operation, the crucible is charged with the metal to be melted and fuel is placed on the grate around it. The top 6 and pipe 16 are put in place, the door 5 and damper 8 are opened, and the damper 15 is closed. 50 The fuel is ignited and as soon as it is in active combustion the damper 8 is closed and

the damper 15 is opened, whereupon the burning gases rising from the fuel pass inward over the edge of the crucible, thence downward over the metal therein, and 55 finally upward through the passages 16, 11 and 14 into the draft-pipe 7, as indicated by the arrows. The metal is thus heated both indirectly by the heat conducted through the crucible and directly by the burning gases 60 passing downward over its surface, and is soon melted. The gases entering the crucible, being of a reducing character and containing a considerable percentage of carbon monoxide, exclude air from the metal and effect reduction of any oxid rising to its surface. Hydrogen or other gases may be supplied to the furnace-chamber through the pipe 18, if desired. The operation may be watched 65 through the peep-hole 13, and the molten metal may be stirred by removing the cover 12 and inserting a rod through the passages 11 and 16. The molten metal may be tapped out through the opening 19, or if the furnace and crucible are small, the top 6, with its 70 pipes 16, 11 and 14, may be lifted off and the crucible then removed by tongs and 75 tilted to discharge its contents.

I claim:

1. A furnace for melting metals, comprising a casing, a fuel-grate, a crucible, a draft-inlet beneath said grate, a draft-pipe connected to the furnace-chamber above said grate, and a tube depending into said crucible and connected to said draft-pipe. 80

2. A furnace for melting metals, comprising a casing, a fuel-grate, a crucible, a draft-inlet beneath said grate, a draft-pipe connected to the furnace-chamber above said grate, a tube depending into said crucible, a cross-connection between said tube and draft-pipe, and dampers in said cross-connection and draft-pipe. 85 90

3. A furnace for melting metals, comprising a casing having a removable apertured top, a fuel-grate, a crucible, a draft-inlet beneath said grate, a draft-pipe connected to the furnace-chamber above said grate, a removable tube extending through said top and into said crucible, a cross-connection between said tube and draft-pipe, and dampers in said cross-connection and draft-pipe. 95 100

4. A furnace for melting metals, comprising a casing having a removable apertured top, a fuel-grate, a crucible, a draft-inlet beneath said grate, a draft-pipe connected to the furnace-chamber above said grate, a removable tube extending through said top and into said crucible, a cross-connection between said tube and draft-pipe, dampers in

10
said cross-connection and draft-pipe, and a gas-inlet to the furnace-chamber.

In testimony whereof, I affix my signature in presence of two witnesses.

GEORGE E. BEHRENS.
